(57) **CLAIM**

The ornamental design for a charger for a communication device, as shown and described.

DESCRIPTION

FIG. 1 is an isometric view of a first embodiment of a charger for a communication device showing our new design;

FIG. 2 is a top orthographic view thereof;

FIG. 3 is a front orthographic view thereof;

FIG. 4 is a rear orthographic view thereof;

FIG. 5 is a right side orthographic view thereof;

FIG. 6 is a left side orthographic view thereof;

FIG. 7 is an isometric view of a second embodiment of a charger for a communication device showing our new design;

FIG. 8 is an isometric view of a third embodiment of a charger for a communication device showing our new design; and,

FIG. 9 is an isometric view of a fourth embodiment of a charger for a communication device showing our new design, in which the slender ring that encircles each charging slot is shaded for transparency.

The broken lines shown in FIGS. 1-9 are included for the purpose of illustrating environmental elements only and form no part of the claimed design. The bottom view is omitted and forms no part of the claimed design.
